(57) **CLAIM**

The ornamental design for a stackable food and beverage container, as shown and described.

DESCRIPTION

FIG. 1 is a front perspective view of a stackable food and beverage container, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines consisting of unevenly sized lines dash-dot-dash lines in the drawings depict the boundary of the claimed invention and it is understood that the claim extends to the boundary that forms no part of the claimed design.

1 Claim, 4 Drawing Sheets
